TURNTABLE DRIVE

Joseph Erwood, Chicago, Ill., assignor to The Webster Company, Chicago, Ill., a corporation of Illinois

Application February 20, 1939, Serial No. 257,315

5 Claims. (Cl. 74—206)

The following invention, which relates to a turntable drive for phonographs and the like, is concerned with certain improvements by which a simple yet effective frictional drive is maintained 5 between a motor which depends from a supporting base and a turntable mounted to rotate above the base, the entire mechanism being unitary in character so that it may be applied to or removed from a platform forming part of a cabinet 10 or otherwise. More particularly the present mechanism comprises a horizontal off center pivotal mounting for a motor which is suspended below the base with its vertically disposed operating shaft extended upwardly through an opening 15 therein, the shaft swinging with the motor so as to occupy various positions relative to the base and to a floating idler wheel which is movably supported thereon for receiving frictional driving engagement from a roller which may be 20 carried upon the shaft near its upper end; or simply a floating idler wheel interposed in the transmission between a roller on the motor shaft and a circular flange depending from the turntable, the wheel diameter being intermediate that 25 of the roller and flange so that a greater contact area is afforded between the wheel and flange than would be the case if the frictional drive were directly between the roller and flange, the movable mounting of the wheel being such that 30 when advanced toward either the roller or flange it engages with the other with a like variable pressure.

The idler wheel, according to the present mechanism, is mounted above the turntable in a position 35 to engage with the inner face of a peripheral flange depending therefrom. The relationship of the various components of the drive is such that I may utilize a gravity force which tends to swing the motor upon its horizontal axis so that the driving roller affixed to its shaft near the upper 40 end engages with pressure against the idler wheel which is thereby held with pressure against the turntable flange so that a satisfactory frictional driving connection is maintained at all 45 times, extending from the motor below the base to the turntable thereabove.

The mechanism herein described is simple and dependable, it is easily assembled and operated, and it permits of ready exchange of driving rollers 50 of varying sizes, so that a constant speed of operation for the turntable may be assured if a synchronous electric motor be used on alternating currents of different cycles.

These and other objects as will hereinafter 55 appear may be realized from a construction, of which a suggestive embodiment is set forth in the accompanying drawing in the manner following:

Figure 1 is a top plan view of a portion of a 60 turntable broken away to exhibit therebelow the

idler wheel and driving roller, the former movably mounted on a base plate of which a large portion also appears in elevation;

Fig. 2 is a vertical section on an enlarged scale taken on line 2—2 of Fig. 1, showing the mechanism operatively positioned upon a platform; 5

Fig. 3 is a vertical section taken on line 3—3 of Fig. 2;

Fig. 4 is a detail in section taken on line 4—4 of Fig. 1;

Fig. 5 is a view in perspective of a saddle which may be used to furnish a pivotal mounting for the motor; and

Fig. 6 is a fragmentary plan view of a turntable partly broken away to exhibit therebelow a modified transmission which proceeds from a motor having a fixed mounting. 15

The turntable operating mechanism is unitary in character in that it is all mounted upon a base plate B adapted to be rested upon and 20 secured to the platform P of a cabinet or other support, as is customary. The base plate occupies a position over an opening o in the platform and is itself provided with a relatively small aperture a which may, if desired, be elongated in 25 form.

Extending upwardly from the base plate is a post p over which may be fitted the hub h of a turntable T of sheet metal or the like. This post affords a fixed mounting in that its axis remains 30 stationary, and, when positioned thereupon, the turntable is adapted to revolve freely about the post. In its upper region u the post is of reduced diameter to fit within the central opening of an ordinary disk record D when positioned upon the 35 turntable in the conventional way.

According to Figs. 1 to 5, the turntable is provided with a depending peripheral flange f. In engagement with the inner face of this flange is a friction tread t, preferably a band of rubber or 40 the like, which is fitted peripherally about an idler wheel W which is mounted to revolve about a stud s which is carried near the swinging end of an arm A pivotally mounted as at 45 6 upon the base plate. The swinging end of this arm is raised sufficiently to position the idler wheel up close to the turntable so as to be normally concealed from view.

From the base plate which is desirably of sheet metal is struck a pair of bracket arms b which 50 depend below the platform for an appreciable distance. Each arm near its lower end is apertured to receive a bushing 7 formed therethrough with an axial opening, 8 to receive a trunnion 9, two such trunnions being extended outwardly, one 55 from each end wall 10 of a saddle 11. The trunnions, as best shown in Fig. 5, are formed adjacent one vertical edge of the saddle so as to occupy an off-center position relative thereto. When supported between the two bracket arms, the saddle 60

idle is free to swing within the bushings which furnish mountings therefor.

Carried upon the saddle is a motor M, desirably a synchronous electric motor, whose field 14 is connected to the saddle as by spaced bolts 15 which support at their upper ends a cross bar 16. Upon the under side of the saddle is secured a strap 17, a similar strap 18 being affixed to the upper side of the cross bar. A shaft S which is connected to the armature 19 of the motor extends vertically from a thrust bearing 20 in the lower strap 17 through a second bearing 21 in the upper strap 18 and thence through the aperture a in the base plate to terminate adjacent the under side of the turntable where I have affixed a driving roller 22 which lies adjacent the tread of the idler wheel. Fitted around the periphery of the roller I have shown a friction tread band 23 of rubber or other appropriate material.

By reference to Fig. 2 it will be observed that the motor, which is of generally symmetrical form, is pivotally supported off-center so that its shaft and preponderance of weight lies to the side of the saddle which is toward the idler wheel.

By reason of this fact the motor tends to swing upon its pivotal support in a direction which will advance its driving roller 22 against the idler wheel which, in consequence, may be swung upon its pivotal mounting toward the inner face of the turntable flange. I accordingly utilize gravity force, obtainable by the off-center mounting of the motor, (1) to advance the driving roller against the idler wheel and (2) to advance the idler wheel against the turntable flange.

If the turntable be removed from its pivot post there is no longer any restraint to swinging movement of the motor which is free to tilt as far as permitted by the confines of the aperture a through which the shaft is extended. This aperture need not be very large—just long enough to afford to the shaft a range of movement which will assure an effective engagement with the idler wheel under operating conditions. With the shaft swung over against one edge of the aperture which serves as a stop therefor the idler wheel is also swung around a corresponding distance, this movement requiring the pivoted arm to swing about its pivot point 6. The parts are therefore displaced from their normal operating positions but very little when the turntable is removed. Upon replacing the turntable, the depending flange thereof is brought against the tread of the idler wheel, after which the turntable is moved over to the required position for fitting upon its pivot post. In reaching this position, the idler wheel moves with the turntable flange with the result that the shaft is finally brought back to its normal operating position which, as shown in Fig. 2, is substantially vertical.

Experience has proven that a small diameter driving roller, when engaged with the concave face of a large diameter peripheral flange of a turntable, will not establish a satisfactory frictional transmission therefor. This is due in large part to the small area of the contact surface between the roller and the flange, consequent upon the wide difference in diameter of these parts of the transmission. The present transmission affords a much more effective contact between the driving roller and the idler wheel on account of the frictional properties of their engaging surfaces, and between the idler wheel and the turntable flange, due to the reduced differences in the diameters of their interengaging surfaces.

As shown, the driving roller is removably af-

fixed to the motor shaft. This is desirable because it permits the ready substitution of another roller of different size. If the motor be a synchronous electric motor designed to operate on a 50 cycle alternating current, the driving roller should be of a different size than in the case of a motor which is designed to operate upon a 60 cycle current, if the speed of turntable rotation is to remain the same. By the simple expedient of using a driving roller of proper size, the correct turntable speed may be assured.

It will be noted that the base plate carries all the parts of the present operating mechanism, being provided on its upper face with a fixed mounting for the turntable and with a movable mounting for the idler wheel, and on its under face with a support wherein the motor is pivotally mounted in an off-center position so as to utilize the force of gravity for swinging itself and the upper shaft end against the idler wheel which, in turn, is pressed against the turntable flange, all assuring a satisfactory frictional engagement so that there is no slippage in the transmission. The supports for the motor are desirably formed by striking from the body of the base plate arms which are depended from its lower face, thereby obviating the provision of extra parts, or any assembly of such parts with the remaining mechanism. In addition, the aperture through the base plate through which the shaft is extended is of a size sufficient to permit the necessary range of swinging movements, yet small enough to limit this swinging movement to a short distance. The opening in the platform is somewhat less in size than is the base plate, so that the edges of the latter may rest upon the platform for securement thereto, but permitting the base plate, when disengaged therefrom, to be lifted together with the motor supported therebelow, the motor then passing through such opening in the platform without interference therefrom. All these factors contribute to ease and simplicity in the assembly and care of the present mechanism which has been found by experience to provide a very satisfactory transmission adapted to accommodate itself to possible irregularities in the turntable flange or even to slight differences in the diameters of such flanges.

In Fig. 6 I have shown a modification of the transmission which is adapted to be used with a motor having a fixed mounting. In this case the roller 22 at the upper end of the shaft rotates in a fixed position; consequently any variation in frictional pressure between the roller and idler wheel W must result from movement of the latter alone. This I accomplish by mounting the roller on an arm A one end of which is rested on the base plate B and provided with a slot 25 through which is entered a securing pin or rivet 6. The wheel so mounted is free to swing upon the pin as a pivot, and also to slide within the limits of the slot wherein this pin is entered. The wheel diameter is such that it occupies a position between the roller and the flange f of the turntable T so as to transmit motion from one to the other.

In order that the wheel may bear with pressure against both the roller and the turntable flange, I provide a light spring such as the tension leaf 26 having a fixed mounting upon a lug 27 which upstands from the base plate, the free end of the leaf bearing with pressure against the arm A which supports the wheel. By this means there is maintained a constant pressure of the wheel against both the roller and the turntable flange such that a necessary degree of friction is main-

tained for the transmission of motion from the motor to the turntable.

In the construction last described the advantages of a floating idler wheel are retained. In 5 the case of irregularities in the turntable flange, or of a slight bend in the motor shaft, the idler wheel may shift its position slightly, as required for accommodation of itself between these two elements in the transmission system. Also, in the 10 case of turntables whose flanges may vary slightly in diameter, the idler wheel is enabled to adjust itself, under tension of the spring 26, so as to establish a satisfactory driving connection from the motor. In accomplishing this, a greater area 15 of surface contact is afforded at the points of frictional connection with the turntable, due to the use of an intermediate idler wheel of substantial diameter, than would be the case if the drive proceeded directly from the roller to the 20 turntable flange.

I claim:

1. In a phonograph, the combination of an apertured base plate affording upon its upper side two mountings, one fixed and the other movable, a turntable provided with a depending flange adapted for rotatable fitting upon the fixed mounting and an idler wheel adapted for peripheral driving engagement with the turntable flange supported on the movable mounting, a fixed support depending from the base plate, a motor having an off-center horizontal pivotal mounting on the support, a shaft extended upwardly from the motor through the base plate aperture, and a roller carried by the shaft near its upper end 25 adapted to frictionally engage the idler wheel, the preponderance of motor weight lying to the side of the axis of its pivotal mounting which is toward the idler wheel whereby the roller end of the motor shaft tends by gravity to bear with 30 pressure against the idler wheel and to hold the idler wheel with pressure against the turntable flange to maintain a driving connection therebetween.

2. In a phonograph, the combination of an 45 apertured base plate of sheet metal, a fixed mounting extending upwardly from the base plate, a swinging mounting extending upwardly from the base plate, two arms struck from the base plate and depended therebelow in spaced 50 relation, a saddle pivotally supported between the two arms, a motor carried on the saddle with preponderance of its weight lying to the side of the pivotal axis of the saddle which is toward the pivotal mounting above the base plate, a turntable 55 having a depending flange adapted to be fitted rotatably upon the fixed mounting extending above the base plate, an idler wheel carried near the free end of the swinging mounting on the base plate adapted for peripheral engagement 60 with the turntable flange, a shaft extended upwardly from the motor through the aperture of the base plate, and a driving roller carried by the shaft near its upper end in a position adapted to engage the idler wheel, the off-center mounting 65 of the motor causing the upper shaft end to normally swing over into engagement with the idler wheel and the latter to swing over into engagement with the turntable flange whereby a driving connection therebetween is maintained.

3. In a phonograph, the combination of an 70 apertured base plate affording upon its upper side two mountings, one fixed and the other movable,

a turntable provided with a depending flange adapted for rotatable fitting upon the fixed mounting and an idler wheel adapted for peripheral driving engagement with the turntable flange supported on the movable mounting, a pair of arms struck from the base plate and downwardly extended therefrom in spaced relation, a motor having a mounting below the base plate between the two arms, a shaft extended upwardly from the motor through the base plate aperture, and a roller carried by the shaft near its upper end adapted to frictionally engage the idler wheel, the motor mounting between the depending arms below the base plate being movable to permit the upper end of its shaft, and the driving roller thereon, to advance toward the idler wheel and to press the latter against the turntable flange whereby to maintain a frictional driving connection therebetween.

4. In a phonograph, the combination of a platform through which is an opening, and a motor turntable unit comprising an apertured base plate mounted on the platform over the opening, a shaft extending vertically through the base plate aperture, a roller affixed to the shaft near its upper end, an arm pivoted to the base plate adapted to swing thereon in a horizontal plane, an idler wheel rotatably carried by the arm adapted to receive peripheral engagement from the shaft roller and to be driven thereby, a post 20 upstanding from the base plate, a turntable 25 rotatably mounted on the post and formed with a depending flange adapted to receive peripheral engagement from the idler wheel, a motor having a rotor in operative connection with the shaft positioned below the base plate, and means depending from the base plate affording a pivotal support for the motor at a point off center and away from the idler wheel axis whereby the motor tends by gravity to force to swing about a horizontal axis in a direction which normally holds the shaft roller against the idler wheel and the latter against the turntable flange to 30 maintain a driving connection therebetween.

5. In a phonograph, the combination of an 45 apertured base plate affording upon its upper side two mountings one being movable, an idler wheel 50 floatingly supported on the movable mounting, a turntable fitting upon the other mounting and provided with a depending flange adapted to be frictionally engaged by the idler wheel, a motor carried by the base plate and supported from a point therebelow, a shaft extended through the base plate aperture to a point adjacent the idler wheel, a driving roller carried by the shaft near the upper end thereof adapted for engagement with the periphery of the idler wheel, the idler wheel affording a floating transmission element between the driving roller and the turntable flange, and means comprising the support 55 for the idler wheel operating to maintain a yieldable pressure contact between the idler wheel and the driving roller and to hold the idler wheel with pressure against the turntable flange and cooperating with the movable mounting of the idler wheel to maintain during rotation of the turntable floating action of the idler wheel with 60 relation to the flange of the turntable as may be required by irregularities in the turntable flange and to accommodate turntables having flanges 65 varying slightly in diameter.

JOSEPH ERWOOD.
